Patented July 25, 1916.

UNITED STATES PATENT OFFICE.

EUGENE W. SCHNEIDER, OF NEW YORK, N. Y.; ELIZABETH CATHERINE SCHNEIDER
EXECUTRIX OF SAID EUGENE W. SCHNEIDER, DECEASED.

APPARATUS FOR AIDING THE HEARING.

1,192,122.

Specification of Letters Patent. Patented July 25, 1916.

Application filed September 3, 1915. Serial No. 48,755.

To all whom it may concern:

Be it known that I, EUGENE W. SCHNEIDER, a citizen of the United States, residing at New York, in the county of 5 Queens and State of New York, have invented certain new and useful Improvements in Apparatus for Aiding the Hearing, of which the following is a full, clear, and exact description.

10 This invention relates to telephonic devices for aiding the sense of hearing, said devices consisting, in general, of a telephonic "transmitter" and a "receiver" connected therewith, the first receiving the 15 sound-waves and translating the same into current-pulsations in the circuit, which are re-translated into sound-waves by the "receiver" at the ear of the user. Inasmuch as the amplitude of the sound-waves produced 20 by the receiver, in other words, the loudness of the sound issuing from the receiver, depends upon the strength of the current, it has been proposed to provide the receiver 25 with an adjustable resistance, or rheostat, whereby the strength of the current and consequently the loudness of the sound can be regulated to suit the needs or wishes of the user. As it is usually, if not always, impossible for the user to know in advance 30 how much resistance should be thrown into or cut out of the circuit to give the best results, the customary practice is to make the necessary adjustment after the receiver is applied to the ear. This method, however, 35 leaves much to be desired. In the first place, the receiver must be held and the controller lever shifted by the same hand (unless the receiver is held to the ear by a head-band), so that adjustment cannot be made as conveniently or as expeditiously as may be desired. The worst feature, however, is the 40 loud and startling click produced each time the lever moves off one point of the resistance and on to another, the sounds thus 45 produced being often sufficient to drown all others and thus make it impossible for the wearer to hear the extraneous sounds that he desired to hear.

The object of the present invention is accordingly to improve such device.

The most important respect in which it differs from the prior devices is that the rheostat or variable resistance is carried by the transmitter instead of by the receiver. Singularly enough, the annoying clicks

caused by adjustment of a rheostat on the receiver are greatly reduced in intensity, and in fact are often scarcely audible at all, when the rheostat is mounted on the transmitter. I also make the adjusting member 60 capable of complete rotation instead of merely a limited swinging movement, and by this improvement it is possible for the user to change from the last point to the first, or vice versa, at will, without moving 65 the adjusting member through all the intermediate steps. This is a feature of considerable value in practice, as it enables the user to change instantly from maximum to minimum, or from minimum to maximum, 70 without passing through a number of intermediate steps with their attendant "clicks".

Other novel features will be made apparent by the following description of the preferred embodiment of the invention, which 75 embodiment is illustrated in the accompanying drawing.

Referring now to the drawing: Figure 1 shows the external appearance of the apparatus, the back of the transmitter and the 80 front of the receiver being shown. Fig. 2 shows the transmitter from the front, on a larger scale, with part of the front wall of the casing broken away to disclose the inner parts. Figs. 3 and 4 are sections on lines 85 3-3 and 4-4, respectively, of Fig. 2. Fig. 5 is a section on line 5-5 of Fig. 3. Fig. 6 is a section on line 6-6 of Fig. 1.

In the embodiment illustrated, which is the preferred but by no means the only form 90 that the invention may take, the transmitter 10 is provided on its back with terminals 11, 12, in the form of sockets, fitting the terminals 13, 14 of the battery 15. The battery terminals, in the form of split plugs, are 95 of different size, and the transmitter terminals differ correspondingly, so that in replacing the transmitter after detachment from the battery or in applying it to a fresh battery, the connection must always be so 100 made as to give a constant polarity. The casing of the transmitter is composed of a box 16 and a screw-cover 17. To prevent opening of the casing by the unskilful user the cover is locked on the box by a pointed 105 device 18 controlled by a cam 19, Figs. 2 and 5. With the cam in the position shown, the point of the device 18 is held out against the contiguous threads of the cover, so that if the attempt is made to unscrew the latter 110

the point will bite into the metal (preferably aluminum) and so prevent further turning. The cam is controlled by a screw 20, Fig. 6, to which it is securely fastened. The head of the screw is concealed under the flexible cord 21 which connects the transmitter with the receiver 22 and which is held securely in place by the clamping strip 23. When the strip is detached at one end and 5
10 swung aside, the cam 19 can be turned by applying a screw driver to the screw 20, whereupon the spring 23, Fig. 2, retracts the pointed device or bolt 18. The cover can then be unscrewed and replaced with ease.
15 Inside the transmitter casing and fastened to, but insulated from, the back thereof is a microphone electrode 25, in the usual form of a carbon disk having pockets containing globular carbon in contact with the 20 vibratory diaphragm 26. At the rear this electrode is connected by a terminal 27 to one of the conductors of the cord 21, the other conductor being connected to the terminal 28, which, like the electrode 25 and its 25 terminal 27, is insulated from the casing. Inside the casing the terminal 28 is connected by a strip 29 to one of the contact "points" 30 of the rheostat or variable resistance (hereinafter described). The opposite end 30 of the resistance coil 31 is connected by the wire 32 to a strip 33 which is itself in electrical connection with the outer terminal 11,—the latter being insulated from the casing while the outer terminal 12 is in connection 35 therewith. It will therefore be seen that the path of the current, beginning, for instance, at terminal 14, is through terminal 12, casing 16, diaphragm 26, microphone electrode 25, to the receiver 22 and back through the 40 cord 21 to terminal 28 and strip 29, thence through the coil 31 (or part of the same), strip 33 and terminal 11 to the battery terminal 13.

The resistance coil 31 is rigidly mounted 45 in any convenient manner on an insulating plate 34 fastened securely in the back of the transmitter casing and supporting the "points" 30, arranged in circular fashion around the coil. These points are conveniently composed of small brass nails fitted tightly in the plate 34 with their heads outside, and are connected at their inner ends to taps so brought out from the coil as to divide the latter into parts, preferably equal. 50 Extending outwardly from the strip 33 at the center of the series of points 30 is a fixed standard in the form of a bolt 35, having a nut 36 by which it is held in place. Fixed to the head, outside the casing, is a 55 pointer 37, and under the pointer is a hollow rotatable finger piece or button 38, preferably graduated as shown. Inside the finger piece is a spring terminal 39 having a central aperture through which the bolt 35 extends. One end of the terminal 39 is fixed

to the side of the button and the other end is free to bear with spring pressure on the points 30; the terminal serving also to press the button snugly against the pointer 37 and thus hold the button in place without the necessity of carefully fitting the edge thereof to the plate 34. If desired, the end of the terminal which bears on the points 30 can be given a shallow groove to engage the rounded points, thus holding the terminal 70 yielding on the point on which it happens to be resting. The finger button and terminal are, however, easily turned in either direction to cut resistance into or out of the circuit and thereby decrease or increase the 75 loudness of the sound delivered by the receiver.
80

It is to be understood that the invention is not limited to the structure herein specifically illustrated and described but can be 85 embodied in other forms without departure from its spirit and scope.

I claim:

1. A telephonic apparatus to aid the hearing, comprising a transmitter having a casing, the said transmitter being provided with a resistance inside of its casing, a circular series of contact points connected with the resistance, a rotatable terminal adapted to engage any one of the points, a rotatable finger-piece outside the transmitter casing to rotate the said terminal, and a scale and pointer to indicate the point on which the terminal rests, the said scale and rotatable finger piece being adapted to cover and prevent tampering with the contact devices. 90
95

2. In a telephonic apparatus for aiding the hearing, the combination with a transmitter having a casing, of a resistance arranged inside the transmitter casing and having a terminal in circuit with the transmitter, a circular series of contact points carried by the transmitter casing and electrically connected with the resistance, a finger-piece rotatably mounted on the casing outside the same, and a terminal rotatable by said finger-piece in engagement with said contact points and electrically connected in circuit with the transmitter, said contacts and rotatable terminal being covered by the 100 aforesaid finger-piece. 110
115

3. In a telephonic apparatus for aiding the hearing, the combination of a transmitter having a circuit and a casing forming part of said circuit, an insulating plate mounted in the back wall of the casing, a resistance mounted on the plate inside the casing and having a terminal in said circuit, a circular series of contact-points connected to different points of the resistance and carried by said insulating plate, a rotatable finger button carried by the plate outside of the transmitter casing, a rotatable terminal actuated by said button and co-operating with said contact-points, and an electrical 120
125

130

connection between the rotatable terminal and said circuit.

4. In a telephonic apparatus for aiding the hearing, the combination of a transmitter having a conducting casing, a plate of insulating material set in the back wall of the casing, a resistance coil mounted on the insulating plate inside the casing, a circular series of contact points surrounding the coil and extending from the outside through said plate and connected to the coil inside the casing, a finger button concentric with the circular series of contact points and rotatably mounted on said insulating plate outside the transmitter casing, and a conducting terminal carried and rotated by the finger button to engage the said contact points.

5. In a telephonic apparatus for aiding the hearing, the combination of a transmitter having a casing, a resistance mounted inside the casing, a circular series of contact points insulated from each other and extending through a wall of the casing and connected to the resistance, a post mounted on the outside of the casing at the center of said circular series of contact points and having a head, a finger button comprising a disk rotatable on the post and having a

peripheral flange extending toward the circular series of contact points outside thereof to conceal the same, and a spring terminal carried by the finger button to engage the contact points and press the finger button outwardly against the head of said post. 35

6. In a telephonic device for aiding the hearing, in combination with a transmitter having a conducting casing; a plate of insulating material set in the back wall of the casing; a resistance coil mounted thereon within the casing; a series of contact devices surrounding the coil and extending through the insulating plate, each of said contacts having a tap connected with the coil, said contacts being arranged in a circle; a finger button concentric with the said contacts and rotatably mounted on the said insulating plate, and a conducting terminal carried by and rotated by the finger button and adapted to engage the contact points, said circular arrangement of contact points permitting the conducting terminal to be shifted directly from the first contact to the last without passing over the intermediate contacts substantially for the purpose described. 50 45 55

In testimony whereof I hereunto affix my signature.

EUGENE W. SCHNEIDER.
